UNITED STATES PATENT OFFICE

2,354,363

MEANS FOR HEATING THERMOPLASTIC MATERIALS FOR MOLDING

Arthur A. Burry, Toronto, Ontario, Canada

Application April 23, 1943, Serial No. 484,296

8 Claims. (Cl. 18—30)

This invention relates to improvements in the construction of the means for heating thermoplastic material as it is fed to the molds or dies, and the principal object of the invention is to provide an apparatus capable of operation free from leakage of the heating medium under excessive temperatures and pressures and to devise a structure which may be manufactured at reasonably low cost and which will be simple and easy to assemble.

The principal feature of the invention consists in the novel construction and arrangement of a hollow core to be supported within a cylinder through which the thermo-plastic material is forced which is surrounded by a sealed jacket provided with an immersion electric heating unit arranged at the bottom thereof below the bottom of the cylinder to generate steam and effect the continuous flow thereof around the cylinder to create and maintain a substantially uniform temperature surrounding the cylinder to plastify the contents thereof, whereby communication between the steam jacket surrounding the cylinder and the interior of the core is maintained through ducts formed in the cylinder registering with ducts formed in the core and communicating with the central chamber thereof, the sealing of the juncture of the ducts of the core and the cylinder body being effected with compression sealing.

In the accompanying drawings

Figure 1 is a longitudinal mid-sectional view of a thermo-plastic heating cylinder constructed in accordance with this invention, the section being made on the line 1—1 of Figure 2.

Figure 2 is a transverse section of the device taken through the line 2—2 of Figure 1.

Figure 3 is an elevational view of the discharge nozzle end of the device partly broken away.

Figure 4 is a longitudinal sectional view of the nozzle end of the cylinder taken on the line 4—4 of Figure 2.

Figure 5 is an elevational detail of the inward end of the core.

Figure 6 is a transverse section on the line 6—6 of Figure 1.

In my United States Patent 2,115,940, dated May 3, 1938, I disclosed a Plastic injection device in the form of a cylinder having a discharge orifice and provided with pressure means for ejecting the cylinder contents with the cylinder surrounded by a sealed jacket spaced therefrom and in which an immersion electric heating unit was arranged at the bottom of the jacket below the bottom of the cylinder, said jacket containing a body of water surrounding the heater whereby steam

was generated to maintain a continuous flow around the periphery of the cylinder to create and maintain a substantially uniform temperature surrounding the cylinder to plastify the contents thereof.

For certain classes of work it was found desirable to arrange a hollow core within the cylinder through which the steam from the jacket could be circulated to more effectively apply heat to the thermo-plastic being forced through the cylinder.

The structure illustrating an application of a hollow steam-heated core is disclosed in my co-pending application No. 308,549, of December 11, 1939, now U. S. Patent No. 2,319,439, dated May 18, 1943.

Certain classes of thermo-plastic material and the molding of certain articles from thermo-plastic material require extremely high temperatures and pressures, and the present invention has been devised in order to obviate leakage of the heat-transmitting fluid in the form of high pressure steam.

In the construction herein illustrated the cylinder 1, in which the plastic material is confined, is surrounded by a cylindrical jacket 2 which is spaced from the outer surface of the cylinder and is provided with inturned end flanges 3 and 4 which form a sealed joint with the outer surface of the cylinder wall. The jacket and the cylinder are assembled with a tight driving fit and, being both constructed of metal of the same coefficient of expansion, a pressure tight joint is effected as each of the flanged ends of the jacket are under extremely high pressures and temperatures.

The end of the jacket remote from the discharge end of the cylinder is provided with a transverse chamber 5 which extends below the bottom of the interior of the jacket 2 and supported therein is an electric heating element 6 which is immersed in a body of water 7. When current is applied to the heating element 6 steam is generated and this circulates around the perimeter of the cylinder 1 and maintains a constant application of temperature to the entire perimeter of the cylinder.

It will be understood that owing to the extreme elasticity of steam the instant that heat is absorbed therefrom it will be replaced by the constantly circulating steam body and condensation will immediately return to the heating chamber 5. This principle has been effectively proven in extensive commercial use of heaters made in accordance with my Patent No. 2,115,940.

It has been found expedient to provide a dome

to the steam chamber and this is arranged in the form of a recess 8 formed in the topside of the jacket 2, preferably above the chamber 5, and a suitable gauge 9 is connected with this recess through the orifice 10. An orifice 11 is provided for the purpose of inserting water into the device and this is closed by a suitable plug 12. In the bottom of the chamber 5 are arranged a pair of obliquely disposed orifices 13 and 14. These are closed by suitable safety fuse plugs 15 which may be arranged to blow at any desired maximum pressure.

At the nozzle or discharge end of the cylinder the cylinder wall is drilled inwardly from the ends to form a plurality of ducts 16 which connect with radial ducts 17 which open through the outer wall of the cylinder into the space enclosed by the jacket 2 so that a plurality of ducts communicate with the steam jacket and lead outwardly to the end of the cylinder. The end of each of the ducts 16 is counterbored, preferably with a taper counterbore 18 and into each of these counterbores is fitted a compression seal 19 in the form of a ferrule of copper or other suitable ductile metal.

The end face of the cylinder is formed with a counterbore 20. A circular head 21, adapted to fit snugly into the counterbored end of the cylinder 1, is provided with a cylindrical core extension 22, the outer perimeter of which is spaced from the inner wall of the cylinder 1. This core is preferably pointed at its inner end to direct the thermo-plastic material outwardly between the outer wall of the core and the inner wall of the cylinder. The core is preferably supported adjacent to its inner end by suitable fins 23.

The face of the head which engages the counterbored end face of the cylinder 1 is formed with tapered counterbored recesses 24 which register with the counterbored recesses 18 in the end of the cylinder and which receive the projecting ends of the compression seal members 19 when the head is placed in position. The compression seal members are bored and communicate with holes 25 which are aligned with the ducts 16 by the compression sealing members.

Diagonal ducts 26 are bored in the head 21 to communicate with the outward ends of the holes 25 and open inwardly into the hollow interior 27 of the core 22, the outer ends of the ducts 26 beyond the holes 25 are sealed with suitable plugs 28.

From this description it will be understood that a plurality of ducts form communicating passages with the steam jacket surrounding the cylinder and the centre of the core 22, and steam entering the chamber 27 of the core circulates freely and condensation will be carried out through the lower duct into the bottom of the steam jacket to find its way to the steam-generating chamber described.

The head 21 is provided with a threaded counterbore 29 which has a central conical projection 30 and a plurality of holes 31 are bored through the head portion in groups arranged between the ducts 26 and leading from the annular space between the inner cylinder wall and the external wall of the core 22. These holes are shown in the form of groups of tapered holes but they may constitute open passages and they are aligned with the tapering wall of the conical projection 30 so that the thermo-plastic material which is forced through the cylinder flows out through the tapered holes or passages and around the conical projection 30. A suitable nozzle 32 is

threaded to the threaded counterbore 29 and its inner wall is tapered and spaced from the conical projection 30 so that the heated thermo-plastic flows out through the single discharge orifice of the nozzle.

It will be noted that the chamber 27 in the interior of the core is cone-shaped at both ends to extend into the conically formed ends of the core and a substantially uniform thickness of metal in the core conducts heat from the circulating steam through this wall to plastify the material as it is forced through the annular passage between the core and the cylinder wall.

The head 21 is formed to fit snugly into the counterbores of the end of the cylinders and it is secured firmly in position by a plurality of cap screws 33 which are threaded into threaded holes 34 arranged in the end of the cylinder and spaced between the ducts 17.

It will be readily appreciated that the close-fitting surfaces of the head 1 and cylinder ends will prevent the escape of the thermo-plastic material that is being forced through the cylinder and the compression seals 19 may be compressed by the tension of the cap screws 33 to hold any required pressure of steam that may be used in sealing the ducts communication between the steam jacket and the interior of the core.

It will be understood from this description that the structure of the device is simple and it may be manufactured very readily at very moderate cost.

When the cylinder and head are machined and ready for assembly the conical compression seals are simply inserted in the counterbored recesses, the head and cylinder are placed together and the cap screws are drawn up tight to complete the seal concurrently of the cylinder and the steam jacket and passages.

With a device such as described extremely high temperatures may be applied to plastify the thermo-plastic material without danger of burning the material and a constant and uniform condition of molding may be maintained.

It is found desirable to provide for the release of air which may be trapped within the steam chambers and I provide a pipe 35, preferably inserted into the dome 8 and provide same with a suitable valve (not shown) to facilitate such removal.

What I claim as my invention is:

1. A means for heating thermo-plastic materials for molding, comprising a cylinder having an open end surrounded by a steam jacket, said cylinder having ducts formed therein communicating with the steam jacket and leading to an end surface, a head closing the open end of the cylinder and having a hollow core extending into and spaced from the cylinder wall, said head having ducts communicating with the ducts in the cylinder and leading into the hollow core, and means for pressure sealing the juncture of the ducts of said cylinder with the ducts of said head.

2. A means for heating thermo-plastic materials for molding, comprising a cylinder having an open end and surrounded with a steam jacket and having ducts formed therein leading from the steam jacket to the open end of the cylinder, a head abutting the open end of the cylinder and having a hollow core extending into the cylinder, ducts in the head aligned with the ducts in the cylinder wall and leading inwardly to the hollow core, the adjacent meeting ends of said cylinder and head ducts being counterbored, per-

forated compressible sealing members seated in said counterbores and joining the ducts, and means for drawing the head into sealed contact with the end of the cylinder.

3. A device as claimed in claim 2 in which the counterbores in the adjacent meeting ends of the head and cylinder ducts are tapered, the compressible sealing members being in the form of tapered metallic ferrules inserted in said counterbores and pressed into sealing engagement therewith.

4. A device as claimed in claim 1 in which passages leading from the interior of the cylinder extend through the head between the ducts connecting the steam jacket with the hollow core, said passages leading to a discharge orifice in the head.

5. A device as claimed in claim 1 in which the head is formed with a counterbored recess in its outer side provided with a central conical extension and passages lead inwardly from the base of said conical extension through the head to communicate with the interior of the cylinder to direct the heated thermo-plastic, and a nozzle having a discharge orifice in its inner end is secured in the counterbore of said head, said orifice being spaced from the conical extension of the head.

6. A means for heating thermo-plastic materials for molding, comprising a cylinder having an open end and surrounded by a steam jacket and having ducts leading outwardly from the steam jacket through the open end of the cylinder, a head closing the end of the cylinder having a hollow core extending into the cylinder

and spaced therefrom, ducts communicating with the hollow interior of the core and leading outwardly to align with the ducts extending from the steam jacket through the end of the cylinder, the interior of the core being in cylindrical form and having conical ends and the exterior ends of the core being conical, means for compression sealing the adjoining ducts of the cylinder and head, and means for securing said head in compression sealing contact, said head having discharge orifices leading from the interior of the cylinder.

7. Means for heating thermo-plastic materials for molding, comprising a cylinder having an open end and a steam jacket therearound and having ducts arranged at the top and bottom leading from the steam jacket to an end surface of the cylinder, a head engaging in sealing contact with the open end of the cylinder and having a reduced core extension projecting into the cylinder and spaced from the cylinder and having a pointed end, ducts formed in the head registering with the ducts in the cylinder and leading to the hollow core, means for pressure sealing the adjacent ends of the cylinder and head ducts, cap screws threaded into the cylinder extending through the head and clamping the head to the cylinder end in sealed contact, and discharge passages arranged in said head leading to a common discharge orifice from the interior of the cylinder.

8. A device as claimed in claim 1 having an air release duct leading from the top of the steam jacket.

ARTHUR A. BURRY.
